GAS HEATER RADIANT

De Witt H. Wyatt, Columbus, Ohio

Application August 30, 1948, Serial No. 46,825

1 Claim. (Cl. 126—92)

1

The present invention relates to gas heaters of a type which is positioned on the floor of a room and connected with the conventional gas line. The principal object of the invention is to provide such a heater of simple, compact construction and of attractive appearance, and which is highly efficient in operation.

An important object of the invention is to provide a novel radiant structure of general utility, but which is particularly useful in the type of heater referred to. It is a purpose of the invention to provide such a radiant which will withstand relatively great mechanical and heat shock abuses. It is also a purpose of the invention to provide such a radiant which is attractive in appearance, presenting a multitude of alternating glow points which are visible through the transparent front panel or door of the heater.

In the drawings, which are illustrative of the several forms of the invention:

Figure 1 is a perspective view of one of the double radiants of the present invention.

Figure 2 is a vertical sectional view through one side of such a radiant, and

Figure 3 is a horizontal sectional view of the radiant, taken along the line 10—10 of Figure 2.

While various types of radiants might be usefully employed I have found that most outstanding results are achieved when radiants of the particular design as shown in the drawing are employed. These radiants are manufactured from a ceramic material which reduces the factor of expansion to a minimum, thus reducing the amount of fatigue in the material due to expansion and contraction. These radiants are of a double type, separated by an integral vertical front rib 90, although it will be understood that single radiants identical with each half shown could be used.

Because the interior construction of the radiant is somewhat complex, it is initially formed in separate front and back sections, indicated in Figure 1 at 92 and 94. The back section 92 carries the rear wall of the radiant, and the front section 94 carries the front open wall of the radiant, and after they are molded the front and back sections are suitably secured together. The side walls of the radiant are formed partially by each of the front and back sections.

Each radiant is open at its front, except for the spaced horizontal baffling and strengthening members 96, there being four of these members shown in each section of the radiant. The design and spacing of these baffle members is such as to present a maximum brightness for direct radiation of light outwardly and upwardly from

the radiants. In cross section, the baffle members are substantially triangular and their surfaces are of area and slope with respect to one another as indicated in Figure 2. Alternating with the baffles 96, there are very substantial open spaces 98 in the front wall of the radiant. The baffles 96 have rearward surfaces 100 which slope rearwardly and upwardly toward the rear wall of the radiant, and spaced V-shaped cut-outs 102 are made in the rearward faces of the baffles, thus providing spaced points 104 which are referred to as glow points, in that they are so intimately surrounded by burning gases as to reach a heat which causes them to have a more brilliant appearance than the adjacent ceramic material. The upper forward faces 101 of the baffle members also slope upwardly and rearwardly in converging relation with the faces 100, the respective faces forming a thin top edge in which the glow points 104 are located. Thus, the mass of the glow points is relatively small, causing them to glow brightly.

The rear wall 106 of the radiant section 92 is provided with a plurality of spaced longitudinal ribs 108 which are disposed in alternating relationship with respect to the glow points 104 on the inner side of the front wall of the radiant, whereby said points 104 and ribs 108 are presented toward one another in staggered relation. At the points where the ribs 108 pass between the glow points 104, they are provided with forwardly extending circular portions 110 which are more intimately surrounded by hot burning gases to cause them to reach a brilliant incandescence, thus providing rear wall glow points alternately spaced behind and above the glow points 104 on the front wall. With this arrangement, the entire front of the radiant will appear to have a brilliant incandescence, and the direct radiation of heat and light will be intense.

It will be noted from Figure 2 that while the rear wall 106 of the radiant is in a substantially vertical plane, the forward wall slopes slightly toward the rear wall so that the hollow interior 45 of the radiant becomes increasingly smaller in volume as the top of the radiant is approached, whereby there is a proper utilization of the effect of the burning gases on the glow points referred to, throughout the entire length of the radiant.

With this construction, it will be apparent that the gases are completely consumed, and they are finally discharged through the top of the radiants through their outlet openings 112.

It will be obvious from the above that the 55 relatively heavy baffle members provide a structurally strong front wall, yet alternate openings

of height greater than that of the baffle members are provided. The baffle members, designed and arranged at the angle shown, do not obstruct light radiation to any substantial extent, and the "front black out" effect common to prior art radiants is not apparent. The rising gases are rolled in a streamline pattern as they rise, rather than following a tortuous path interrupted by casual baffle points which violently disturb the upward flow. The design permits development of a high intensity of heat in the hollow shells of the radiants resulting in maximum combustion temperatures. The opposed walls of the radiants assist in heating one another to a marked degree by direct radiation, and the inclined surfaces 100 of the baffle members act repeatedly to turn the rising gases rearwardly toward the back wall of the radiant, avoiding outward and premature discharge of gas which might not be completely consumed. Each baffle serves to direct the gases inwardly toward the upper parts of the adjacent projection 110 and also toward the lower parts of the rows of projections 110 next above.

The forward extensions 110 and adjacent portions of the ribs 108 are heated to the appearance of glow points and they are presented in staggered relation to the forward wall glow points 104 in the thin top edge of the baffle elements 96.

I claim:

A hollow radiant having substantially closed rear and side walls and an open front wall, said rear wall being in a substantially vertical plane and said front wall being in a plane which tapers upwardly and inwardly toward said rear wall to thereby progressively reduce the volume of the hollow interior of the radiant, said front wall comprising a plurality of spaced triangularly shaped baffle members extending trans-

versely between the side walls of the radiant, said baffle members being vertically spaced to provide areas of the rear wall being completely exposed when viewed from the front, each of said baffle members having an inner face sloping upwardly toward the rear wall and an upper face sloping upwardly and rearwardly in converging relation with said inner face to provide a thin upper edge, said baffle members having a plurality of spaced substantially vertical cutouts providing glow points of relatively small mass along the thin upper rear edges thereof, said rear wall comprising a plurality of forwardly extending vertically disposed transversely spaced ribs positioned directly behind the cutouts, and each of said ribs including vertically spaced straight portions connected by curved portions extending outwardly toward the front wall and disposed adjacent the glow points to provide rear wall glow points staggered relative to the front wall glow points.
